FIG. 9

FIGURE 1 is a front perspective view of the combined magnetic tape recorder and video monitor, or similar article, with the cover attached and showing my new design;

FIGURE 2 is a front perspective view thereof shown with the cover removed;

FIGURE 3 is a bottom plan view thereof;

FIGURE 4 is a top plan view thereof;

FIGURE 5 is a front perspective view thereof with the cover removed and with the video monitor in an upright position;

FIGURE 6 is a rear elevational view thereof;

FIGURE 7 is a front elevational view thereof;

FIGURE 8 is a right side elevational view thereof; and

FIGURE 9 is a left side elevational view thereof.

The grill fragmentarily shown by cross-hatching in FIGURES 1, 2, 5 and 7 is continuous within the boundaries indicated. FIGURES 2, 4 and 5 have diagonal lining in the face of the video monitor to indicate transparency.

The dominant features of my design reside in the portions shown in full line.

I claim:

The ornamental design for a combined magnetic tape recorder and video monitor, or similar article, substantially as shown and described.
